UNITED STATES PATENT OFFICE.

HERMAN E. BONSCHUR, OF PHILADELPHIA, PENNSYLVANIA.

EYEGLASSES.

SPECIFICATION forming part of Letters Patent No. 737,327, dated August 25, 1903.

Application filed March 18, 1903. Serial No. 148,355. (No model.)

To all whom it may concern:

Be it known that I, HERMAN E. BONSCHUR, a citizen of the United States, residing in Philadelphia, Pennsylvania, have invented 5 certain Improvements in Eyeglasses, of which the following is a specification.

The main object of my invention is to so construct an eyeglass that the guard and the spring-bow will be rigidly held to the post, so 10 as to prevent the loosening of the screw.

A further object of the invention is to so form the guard that it can be readily adjusted to fit different contours of noses and that the lenses can be brought into any required position 15 before the eyes.

These objects I attain in the following manner, reference being had to the accompanying drawings, in which—

Figure 1 is a view of a pair of eyeglasses, 20 showing my improvement. Fig. 2 is a section on the line 2 2, Fig. 1. Fig. 3 is a detached view of the guard. Fig. 4 is a perspective view showing the guard, posts, and bow detached. Figs. 5 to 16, inclusive, are 25 views showing the guard adjusted to different positions. Fig. 17 is a view of a modification, and Fig. 18 shows an extended head on the guard.

A A are the lenses, to each of which is attached 30 the ordinary post B, having a socket b, formed by two flanges b' b', and each post is secured to its lens, in the present instance by means of clips and a screw. The socket b is deep enough to receive the end of the 35 bow C and an arm d of the guard D. Both the bow and the arm fit snugly between the flanges b'.

On the end of the arm d of the guard D is a head d', forming shoulders d², which rest 40 upon the ends of the flanges b' of the post. The arm d is perforated, as well as the end of the bow C, and passing through the perforations and into the post is a screw e, which confines the guard and the bow to the post. 45 I also provide the bow C in some instances with a head c, so as to form shoulders c', which rest against the under side of the flanges b' b'. When the guard and the bow are secured to the post by the screw, the parts are rigid, as 50 the shoulders prevent any pivotal motion of either the guard or the bow on the screw.

While I have shown the bow provided with

shoulders, it will be understood that in many instances the guard only may be provided with shoulders, as it is the slight movement 55 of the guard in its socket that loosens the screw, it being almost impossible to make a snug fit between the sides of the arm of the guard and the flanges b' b' of the socket, owing to the minuteness of the parts. 60

By forming shoulders on the arm of the guard, which is made of flexible material, its members can be bent and adjusted to any position after the guard is mounted on the post without the liability of straining and bending 65 the flanges of the post, as the pressure is resisted by the ends of the flanges instead of the sides.

It will be understood that eyeglasses must be made of material which will not rust. Consequently they are generally made of ten and fourteen carat gold or German silver, and the flanges of the post have to be so light in order to present a neat appearance that they will not resist the pressure necessary in adjusting 75 the members of the guard to accommodate the nose after the parts are assembled. 70

In some instances I may make the shouledered head on the arm of the guard, as shown in Fig. 18, in which the shoulders i extend 80 rearwardly as well as laterally, so as to bear against the body of the post, so that the lateral strain is taken by the body as well as by the flanges, thus relieving the flanges of the strain. This construction will prevent not 85 only the lateral movement of the guard on the screw as a pivot, but will also resist the strain when the guard is bent to and from the lens.

The body of the guard is made as shown clearly in Fig. 3, having a lower member D', 90 in the form of a scroll, connected to the arm d by a short neck d³, and an upper member D², having its outer edge slightly curved. The upper member projects upwardly at an angle from the source or root of the curve, forming 95 the contour of the scroll member, and preferably extends beyond the end of the arm d. The end d⁴ of the scroll member D' is shaped in the form of a button, as shown, and on the curved member below the member D² is a projection d⁵. This projection, as well as the ends of the members D' and D², is perforated, 100 so that the facing F of celluloid or other suitable material can be properly secured by

means of rivets to the guard when a facing is used.

By making the guard in the manner shown I am enabled to adjust it to fit noses of different contours and to adjust the lenses to any position in front of the eyes. Heretofore it has been generally necessary to provide the dealer with a series of guards, each of which can be very slightly adjusted to accomplish 10 the result attained by my invention.

Figs. 5 to 16 are diagram views illustrating some of the positions to which my improved guard can be adjusted. The views are arranged in pairs. Figs. 5, 7, 9, 11, 13, and 15 are edge views, and Figs. 6, 8, 10, 12, 14, and 16 are rear views. The guard can be adjusted by bending the upper and lower members forward or backward, curling the lower members, twisting the neck or the upper or lower members, and moving the body portion vertically in respect to the arm, the neck allowing for this adjustment.

In Figs. 5 and 6 I have shown the guard bent to fit a nose having a shallow bridge with 25 prominent eyes and forehead.

In Figs. 7 and 8 the guard is illustrated as bent to fit the average nose.

In Figs. 9 and 10 the guard is illustrated as bent to fit a prominent nose and forehead 30 with deep-set eyes.

In Figs. 11 and 12 the guard is illustrated as bent for use on the average nose where it is desired to lower the glasses for reading. This is done by simply curling the scroll portion D', so as to draw it up close to the point 35 where the arm d projects from the guard, and twisting the neck d³ upward.

In Figs. 13 and 14 the lower scroll member is shown bent forward and the upper member bent back, so that the lenses will rest at 40 an angle to the eyes for reading and close observation.

In Figs. 15 and 16 the upper member is bent forward and the lower member bent back, the lenses resting at an angle to the 45 eyes for distance only and so that the wearer can see under the glasses.

It will be understood that other adjustments may be made for extreme cases; but 50 the above will clearly illustrate the flexibility of my improved guard.

When it is desired to adjust the lenses a considerable distance from the eyes, the neck d³ may be lengthened.

55 It will be seen that the bearing of the guard taken as a whole is very wide, and yet the line of bearing is comparatively narrow. The lower scroll member being open at the center forms a pocket for the flesh of the nose to enter. Thus the guard is held firmly to the nose, and the button d⁴ at the extreme end can be bent so as to slightly press against the nose and form a lock to prevent any pivotal movement of the glasses on the nose, and this

60 lock also prevents the guard from sliding forward. By curving the outer edge of the upper member D², I increase the space between

the socket and the said member and enable the upper member to firmly engage the flesh of the nose.

70 In Fig. 17 I have shown a modification of my invention in which shoulders d⁶ are shown in such position on the arm as to rest under the flanges b' of the post. It will be understood that the lateral shoulders may project 75 at any point desired so as to prevent the guard swinging on the screw as a pivot and so that the flanges will be relieved from side pressure.

I claim as my invention—

1. The combination in eyeglasses, of a lens having a post with straight flanges thereon forming a socket, with a guard having an arm mounted in the socket, lateral shoulders on the guard extending over the flanges of the 85 post, and means for securing the guard to the post, substantially as described.

2. The combination in eyeglasses, of a lens, a post secured to the lens, straight flanges on the post forming a socket, a nose-guard having lateral shoulders, and a bow having lateral shoulders, the bow and the guard being mounted in the socket of the post, means for securing the parts to the post, and shoulders resting against the flanges forming the socket, 95 substantially as described.

3. The combination in eyeglasses, of a post, flanges at each side of the post forming a socket, a guard having an arm, an overhanging head on the end of the arm forming lateral shoulders, said shoulders resting against the ends of the flanges of the socket, and a screw securing the guard to the post, substantially as described.

4. As a new article of manufacture, a nose-guard for eyeglasses having an arm, with an overhanging head on the end of the arm forming lateral shoulders extending beyond the body of the arm, substantially as described.

5. As a new article of manufacture, a nose-guard for eyeglasses made of flexible material having an arm by which it is secured to a post, and having a lower scroll member and an upper member projecting upwardly at an angle from the root of the scroll member, substantially as described.

6. As a new article of manufacture, a nose-guard for eyeglasses having a lower scroll member, an arm projecting from the root of the said scroll member and by which the guard is secured to the eyeglasses, an upper member projecting diagonally upward from a point near the root of the scroll member and curved at its outer edge, said members being independently adjustable, substantially as described.

7. As a new article of manufacture, a nose-guard for eyeglasses having a lower scroll member, an upper member projecting at an angle from a point near the root of the lower 130 member, an attaching-arm projecting from the root of said lower member, said arm having a head forming lateral shoulders, substantially as described.

8. The combination in eyeglasses, of a lens having a flanged post forming a socket, a guard having an arm, a flanged head on the arm forming shoulders, the said flanges being bent back so as to rest upon the flanges and the body of the post, substantially as described.

9. The combination in eyeglasses, of a lens, a post secured to the lens, said post having straight side flanges forming a socket, a guard having an arm fitting between the flanges of the post, an overhanging head on the arm of the guard resting upon the upper ends of the

flanges, a lower member in the form of a scroll extending from the arm, and an upper member projecting at an angle from a point near the root of the scroll member and curved at its outer edge, substantially as described.

In testimony whereof I have signed my name to this specification in the presence of two subscribing witnesses.

HERMAN E. BONSCHUR.
